UNITED STATES PATENT OFFICE.

CHARLES WHITE, OF BALTIMORE, MARYLAND, ASSIGNOR OF ONE-HALF TO
MICHAEL HOLZMAN, OF SAME PLACE.

EMBROIDERY-CUTTING MACHINE.

SPECIFICATION forming part of Letters Patent No. 320,031, dated June 16, 1885.

Application filed March 27, 1884. (No model.)

To all whom it may concern:

Be it known that I, CHARLES WHITE, a citizen of the United States, residing at Baltimore, in the county of Baltimore and State of Maryland, have invented certain new and useful Improvements in Embroidery-Cutting Machines, of which the following is a specification, reference being had therein to the accompanying drawings.

10 The object of my invention is to provide a movable knife which is adapted to separate the goods on a line with the outer edge of the embroider. I attain this object by mechanism illustrated in the accompanying drawings, 15 in which—

Figure 1 is a top view with parts removed; Fig. 2, a longitudinal section; Fig. 3, front end view; Fig. 4, an end view showing position of belt-pulleys; Fig. 5, detail view of 20 knife, showing goods partly cut; Fig. 6, same as Fig. 5, with goods removed; Figs. 7 and 8, section views of Figs. 5 and 6; Fig. 9, a detail view showing method of cutting; Figs. 10 and 11, views showing modifications in which 25 an endless band is used, and Figs. 12 and 13 a modification in which the knife reciprocates.

Similar letters refer to similar parts throughout the several views.

The bed-plate A is supported by projecting 30 legs a, which are secured to a frame or table of any suitable kind.

From the under surface of the plate A project hangers b and b', which form bearings through which the shafts C and C' pass. On 35 the ends of said shafts are rubber sleeves c c', which engage with each other and form the feeding device.

To the opposite end of the shaft C is attached the driving-pulley D, which contains two 40 grooves, one being occupied by the driving-belt, the other by the belt d, which passes over the pulley e to the idle-pulley e', thence to the pulley e" on the spindle f from which it returns to the driving-pulley D by passing 45 over a second idle-pulley e, the belt being crossed between the pulleys e" on spindle f, and the idlers e' and e" to move or rotate the knife F in the proper direction in relation to the movement of the goods while being cut.

50 The spindle f runs in the bearings g g, between

which is placed the pulley e", the lower end of the spindle carrying the cutting-knife F, the cutting-edge of which moves in a plane parallel to that traversed by the goods, part of which (as it is cut) passing over the knife F, and the other part passing under to the feed-rollers c, which draw the material forward.

The knife F rotates in a circular opening in the bed-plate A, provided with a slot, g', at one side to allow the goods to pass downward 60 to the feed-rollers c c. On the side opposite to the slot g' of the circular opening is a semi-annular elevation, g", (see detail Fig. 6,) the height of which regulates the distance from the outer embroidered edge to where the goods 65 are separated. The nearer the upper surface of the projection g" is to the surface of the knife-plane the closer the material will be cut to the embroidery, or vice versa.

The semicircular plate h is pivoted at one 70 end to the bed-plate A, which permits it to be moved to and from the knife F, whose function is to prevent the goods from puckering as they are cut, and its position is, when operating, close to the edge of the knife, as seen 75 in Fig. 5.

The material is held in its place by the guide i, supported on the rod i', which passes through the support n, and has an inward and outward movement to accommodate the different size embroidery, and when set in the proper position is there held by means of the thumb-screw i'.

The shaft I runs in bearings l l, suspended from the bed-plate A, and is provided at one 80 end with the pulley e, by which it is driven by the belt d, the other end having a slot, m, in which the cut goods are inserted to be wound into a roll as they pass from the feed-rollers c c. The shaft I and its attachments are not 90 essential to the cutting device, and may be dispensed with, as its functions are only to facilitate the handling of the goods after they are cut.

In operating the machine the guide i is raised 95 and the plate h thrown back, permitting the goods to be placed in position, (a few inches of which are previously cut by hand,) the end containing the embroidery being passed over the knife F, and the other part being 100

passed through the shot g' to the feed-rollers $c c$, thence to the winding-roller or shaft I, and placed in the slot m . The guide i is then placed on the goods with its guiding-surface 5 g^2 bearing against the outer embroidered edge, p , and the plate h moved in or placed around the knife F, the embroidery being placed in relation to the knife so that the inner angles p' of the scallops will just pass within the periphery of the knife F. As the goods are moved 10 forward, the section containing the embroidery is held up, while the other section is drawn down, thus exposing only that portion of the fabric which is in close proximity with the embroidery to the knife's cutting-edge. The 15 knife's cutting-edge moving in a plane parallel with the fabric, any regular or irregular line of embroidery may be cut by this arrangement.

As the gist of my invention is to have the 20 cutting-edge of the knife moving in a plane parallel to that of the surface which supports the fabric, I show modifications, which are illustrated in Figs. 10 and 11, in which an endless band, F, is arranged to run over the wheels 25 B^3 and B^4 with its cutting-edge moving in a plane parallel to the surface of the fabric-supporting surface; with the wheel B^4 , attached to the shaft f , which is provided with the pulley D, by which it is driven, and a bevel gear- 30 wheel, h^4 , that engages with a similar wheel on the shaft C, which operates the feed-rollers c ; and, as shown in Figs. 12 and 13, a reciprocating knife, F, is arranged, likewise, that it 35 will perform the same function, and which is

operated by the connecting-rod h^5 attached to 35 a crank on the shaft f .

Having fully described my invention what I claim, and wish to secure by Letters Patent, is—

1. In a machine for trimming embroidered fabrics, the knife F, in combination with a 40 guiding or supporting surface g^2 , which is parallel to the plane traversed by the cutting-edge of the knife, for the purpose as herein specified.

2. The combination of the knife F, the surface g^2 , parallel to the plane traversed by the 45 knife's cutting-edge, and the feed-rollers $c c$, as herein set forth.

3. The combination of the knife F, the surface g^2 , parallel to the plane traversed by the 50 cutting-edge of the knife, and the plate h , for the purpose as herein set forth.

4. In an embroidery-trimming machine, the combination of the knife F, the guide or supporting surface g^2 , and the slot or opening g' , 55 the whole being arranged to permit that portion of the fabric that is cut from the embroidery to pass on one side of the knife and the embroidered section to pass on the other side, as herein specified.

In testimony whereof I affix my signature in presence of two witnesses.

CHAS. WHITE.
